DESIGN FOR A RADIO RECEIVING SET

Daniel J. Crowley, Grosse Pointe, Mich.

Application February 3, 1936, Serial No. 60,957

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Radio Receiving Set, of which the following is a specification, reference being had therein to the accompanying drawing, forming a part thereof,

wherein; my new design of radio receiving set is illustrated by a perspective view.

The dominant feature of my design consists in the general contour of the radio receiving set which is symmetrical about its vertical axis.

I claim:

The ornamental design for a radio receiving set substantially as shown and described.

DANIEL J. CROWLEY.
